CLAIM

The ornamental design for a gem disk, as shown and described.

DESCRIPTION

FIG. 1 is an isometric view of a gem disk according to an embodiment of the present invention.

FIG. 2 is a top plan view of the gem disk shown in FIG. 1. FIG. 3 is a bottom plan view of the gem disk shown in FIG. 1.

FIG. 4 is a front elevation view of the gem disk shown in FIG. 1.

FIG. 5 is a rear elevation view of the gem disk shown in FIG. 1.

FIG. 6 is a right elevation view of the gem disk shown in FIG. 1.

FIG. 7 is a left elevation view of the gem disk shown in FIG. 1; and,

FIG. 8 is an isometric view of the gem disk shown in FIG. 1 positioned in a gem applicator.

The broken lines in the figures illustrate environmental elements which form no part of the claimed design.

1 Claim, 5 Drawing Sheets
